(57) **CLAIM**

The ornamental design for an automobile body and/or replica, as shown and described.

DESCRIPTION

FIG. 1 is a left side elevation view of an automobile body and/or replica showing our new design;

FIG. 2 is a front elevation view thereof;

FIG. 3 is a right side elevation view thereof;

FIG. 4 is a left, front perspective view thereof;

FIG. 5 is a left, rear perspective view thereof;

FIG. 6 is a top plan view thereof; and,

FIG. 7 is a rear elevation view thereof.

The portions of the automobile body and/or replica shown in evenly spaced broken lines depict environmental structures that form no part of the claim.

1 Claim, 7 Drawing Sheets
